TELEVISION SYSTEM

Karl R. Wendt, Audubon, N. J., assignor to Radio Corporation of America, a corporation of Delaware

Application October 23, 1940, Serial No. 362,312

10 Claims. (Cl. 178—7.1)

My invention relates to television systems and particularly to a method and apparatus for insuring that the synchronizing pulses have the proper amplitude with respect to the picture signal itself at a given point in the system.

The invention is especially useful in systems wherein a portable transmitter of comparatively small power transmits the television signal to a main transmitter having sufficient power to cover the desired service area. It has been found that in such systems the signal is no longer in its original condition by the time it reaches the main transmitter. For example, the synchronizing pulses may have been saturated off a certain amount by the portable transmitter. Also, the signal, by the time it reaches the main transmitter, may contain low frequency errors both as a result of losing low frequency signal components and as a result of acquiring undesired low frequency signal such as 60-cycle hum. Because of this, it may be difficult to transmit to the receivers a signal which contains synchronizing pulses of the proper relative amplitude for good synchronization of the receivers. It will be apparent that, in a sense, the main transmitter is functioning as a relay station in the system just described.

The invention is also useful in transmitting television signals originating from a studio, especially when the studio and the studio television equipment is located some distance from the radio transmitter. In this case, the television signal, a composite signal consisting of picture signal and synchronizing pulses, is transmitted to the radio transmitter either through a long cable or through a radio link. In the latter case, the situation may be similar to that described above where a portable transmitter is employed, although usually the difficulty will not be as great. Where the transmission is through the long cable, one difficulty encountered is caused by the cable acquiring different D.-C. potentials at its ends whereby hum or irregular voltages are introduced into the television signal. In all cases, the system tends to saturate off the synchronizing pulses because of the difficulty in avoiding nonlinearities in the circuit, especially in the amplifiers.

It is an object of my invention to provide an improved method and means for overcoming the above-mentioned difficulties.

More specifically, an object of the invention is to provide in a television transmitter an improved method and means for restoring the

synchronizing pulses to a suitable amplitude with respect to the picture signals.

A further object of the invention is to provide an improved picture transmitter and, particularly, to provide an improved picture transmitter which is being modulated by signals originating at a point remote from the radio transmitter.

In one embodiment of the invention the composite signal, consisting of picture signals and synchronizing pulses, is transmitted from the portable transmitter, received at the main transmitter station and amplified a suitable amount, and then supplied to a circuit which corrects for the low frequency errors in the signal. The low frequency correction preferably is obtained by means of a keyed diode direct-current setter or reinserting circuit.

Next, synchronizing pulses are obtained from the corrected signal and added to the corrected signal at a later point in the circuit whereby, in the resulting signal, the synchronizing pulses have a greater amplitude than they should have when applied to the modulator of the transmitter. The next step is to clip off the synchronizing pulses at a fixed voltage level beyond "black" in the picture, that is, at "blacker than black," whereby the desired signal is obtained for transmission to the receivers. This last clipping action preferably is controlled by a keyed direct-current setter or re inserter operating on the black level.

The invention will be better understood from the following description taken in connection with the accompanying drawings in which

Figure 1 is a circuit diagram illustrating one embodiment of my invention as applied to a television system.

Figures 2 to 6 are curves which are referred to in explaining the invention,

Figure 7 is the plate-voltage plate-current curve of a pentode which is referred to in explaining the operation of one of the D.-C. inserters employed in the embodiment of Figure 1, and

Figure 8 is a group of curves which illustrate the final clipping operation in my invention.

Referring to Fig. 1, the invention is shown applied to a television transmitter, which in the example illustrated receives a composite signal consisting of picture signals and synchronizing pulses by means of a suitable radio receiver indicated at 10. The received signals may have been transmitted from a portable transmitter or from a television studio connected to the main

transmitter through a radio link. The received signal is to the type commonly employed in the United States at the present time for television transmission and consists of picture signals, periodically recurring line synchronizing pulses and periodically recurring framing pulses. The peaks of the synchronizing pulses have been made to go to a fixed voltage level such as a fixed number of volts beyond "black" in the picture before the direct current and low frequency components have been suppressed. This may be accomplished in various ways, as by varying the clipping level of a vacuum tube in the way described in United States Patent No. 2,192,121, issued February 27, 1940, in the name of Alda V. Bedford, or by utilizing a suitable mask with a scanning disc so that the signal goes to "black" at the end of each scanning line.

The radio receiver 10 demodulates the incoming signal whereby there appears in its output the above-described composite signal which may be further amplified by means of an amplifier indicated at 11.

The signal appearing in the output circuit of amplifier 11 will have the general character indicated in Fig. 2 where the picture signal is represented at 12, the synchronizing pulses at 13 and the black level or pedestal at 14. As represented in Fig. 2, the synchronizing pulses 13 are not of sufficient amplitude with respect to the rest of the composite signal for obtaining good synchronization. Also the black level of the picture is not at a fixed voltage level but, instead, follows a level represented by the dotted line 16 which may represent either the presence of 60-cycle hum voltage or the like, or the loss of a low frequency signal component.

In Fig. 2, the pulses 13 are the line synchronizing pulses. It will be apparent that the drawing has been greatly simplified since, for any one cycle of a low frequency hum voltage, there would be a large number of the pulses 13.

Before describing the circuit of Fig. 1, in detail, it may be helpful first to consider what is accomplished by the circuit, especially with reference to Figs. 2 to 6. First, it will be noted that the output of amplifier 11 is fed through a coupling condenser C to an amplifier tube 17 at the input circuit of which "black" in the picture is brought back to a fixed voltage level as illustrated in Fig. 3. Stated differently, there is D.-C. insertion and low frequency insertion and/or correction at the input electrodes of the tube 17.

In the plate circuit of amplifier tube 17, the synchronizing pulses are increased greatly in amplitude by supplying synchronizing pulses, such as represented in Fig. 4, over a conductor 18 whereby the composite signal of Fig. 3 and the synchronizing pulses of Fig. 4 are added in the plate resistor 19 of the tube 17 to produce the signal shown in Fig. 5 of the drawings. The synchronizing pulses 13 now have a much greater amplitude than they should have in the final transmitted signal.

The combined signal is next passed through a coupling condenser 21 to an amplifier tube 22 of the cathode follower type. The amplifier 22 is caused to clip the synchronizing pulses 13 at such a level as to make them of the desired amplitude in the final signal, such a clipping level being indicated in Fig. 5.

As will be described hereinafter, the amplifier tube 22 is made to clip the synchronizing pulses at the proper level by utilizing a "keyed" direct-current reinserting device for reinserting the di-

rect current at the input electrodes of the tube 22.

In the particular example illustrated, this D.-C. reinserter comprises a pentode indicated at 26. Delayed pulses for keying this pentode during the period of black level in the signal are shown in Fig. 6.

The signal output of the amplifier 22, which now contains synchronizing pulses of constant amplitude with their peaks at a fixed voltage level, may be supplied over a cable indicated at 27 (properly terminated by resistor 28) to the main radio transmitter 29.

Referring now to the circuit more in detail, the desired D.-C. insertion and low frequency correction at the input of amplifier tube 17 is accomplished by means of a keyed diode circuit similar to that described and claimed in my co-pending application Serial No. 362,311, filed Oct. 23, 1940, entitled "Direct current reinserting circuit," and assigned to Radio Corporation of America. As explained in my co-pending application, a D.-C. reinserting circuit depends for its operation upon the fact that the height of the synchronizing pulses with respect to the A.-C. axis of the composite signal is a measure of the amount of direct current or low frequency correction to be inserted.

The D.-C. reinserting circuit includes an amplifier tube 31 through which the coupling condenser C receives a charge, the control grid and the cathode of this tube functioning as a diode. It also includes a diode 32 through which the condenser C may discharge a slight amount during the occurrence of a synchronizing pulse in the event that the amplitude of the synchronizing pulses has decreased. As will be explained later, the tube 31 has a double function, since it functions not only as a diode for the D.-C. reinserting circuit but also as one of the clipper tubes in a series of such tubes provided for the purpose of obtaining synchronizing pulses free from picture signal.

The condenser C must receive its charge through the grid-cathode impedance of the tube 31 since, in the specific example being described, the amplifier tube 17 has a rather high negative bias on its control grid 34 due to a cathode resistor 33 which is given sufficient resistance to make the characteristic of tube 17 linear. Preferably, the resistor 33 is variable so that it may be employed as a gain control. The use of the resistor 33 biases the control grid 34 of the tube 17 so far negative that the positive synchronizing pulses applied thereto cannot cause grid-current flow.

The resistor 33 also holds the control grid 34 more negative than desirable for proper amplification of the synchronizing pulses. To overcome this objection, the R.-C. network comprising resistor 36 and condenser 37 is connected next in the control grid of the tube 31 whereby there appears across the R.-C. network a bias voltage which is of the proper amplitude to reduce the bias on control grid 34 to the desired value during the occurrence of a synchronizing pulse. It will be understood that, during the occurrence of a synchronizing pulse, the control grid of the tube 31 is at substantially ground potential because of the low grid-cathode impedance during the flow of grid current.

From the foregoing, it will be apparent that the coupling condenser C is initially charged by current flow through the grid-cathode impedance of tube 31 and that, upon an increase in the am-

plitude of the synchronizing pulses, it receives an additional charge through this same grid cathode impedance. The right-hand or grid side of the condenser C, during the flow of charging current, goes to a potential with respect to ground which is equal to the voltage across the network 36—37. As will be pointed out later, this side of the condenser goes to this same potential upon the occurrence of a synchronizing pulse whether the condenser charges or discharges.

In order to make the diode 32 conducting during the occurrence of synchronizing pulses, and nonconducting during the picture signal intervals, keying pulses are applied through a conductor 41, a resistor 42, and a condenser 43 to the plate of the diode 32, there being a resistor 38 connected between the diode plate and ground. These keying pulses are applied to the diode plate with a positive polarity and are obtained as follows:

The amplifier tube 31 clips off some of the picture signal, as previously described, and supplies the synchronizing pulses to an amplifier tube 44 with negative polarity. The tube 44 functions as a linear amplifier and may be provided with a cathode resistor 46 to make its characteristic more linear.

Synchronizing pulses of positive polarity appear on the control grids of clipping tubes 47 and 48, these tubes having a substantial negative bias thereon which is obtained by giving a grid condenser 49 and a grid leak resistor 51 suitable values for producing grid leak biasing, as is well understood in the art. This grid leak bias is made such that no picture signal appears in the plate circuits of the tubes 47 and 48. It has previously been explained that the synchronizing pulse output of the tube 48 is fed over the conductor 18 to be added to the synchronizing pulses appearing in the composite signal supplied from the amplifier tube 17.

Since the synchronizing pulses appearing in the plate circuit of tube 47 are of negative polarity, they are reversed in polarity by means of an amplifier tube 52 which supplies the synchronizing pulses or keying pulses to the conductor 41. In the example illustrated, the tube 52 is provided with the proper negative bias by means of grid leak biasing. In this instance, it is the signal of comparatively long duration on the positive side of the A.-C. axis that drives the control grid of the tube 52 slightly positive to produce the grid current which maintains the desired bias.

In the event the synchronizing pulses begin to decrease in amplitude, the condenser C will discharge slightly upon the occurrence of a synchronizing pulse. This discharge circuit may be traced from the condenser C through the plate circuit of amplifier 11 to ground, through ground to the plate circuit of tube 52, through the said plate circuit and through conductor 41 to the diode 32 and through a resistor 39 back to the condenser C.

If desired, an additional diode 56 may be provided for the purpose of clipping off the peaks of the keying pulses, especially in the event that the circuit tends to oscillate because of the feedback through the conductor 41. The plate of diode 56 is connected to the junction point of resistor 42 and condenser 43, while its cathode is connected through a resistor 57 to ground. The resistor 57 is shunted by a condenser 58, this condenser and the resistor 57 preferably having such

values that their time constant is longer than the time constant of the circuit including the resistor 38 and the condenser 43 associated with the diode 32. It has been found that this reduces the tendency of the circuit to oscillate.

Next, considering the operation of the D.-C. reinserting circuit comprising the pentode 26, this pentode is keyed by means of a delayed pulse which, in the example illustrated, is provided by means of a vacuum tube 61, which, with its associated elements, forms a nonlinear differentiating circuit of the character described and claimed in my copending application Serial No. 337,158, filed May 25, 1940, entitled "Electrical delay circuits," and assigned to the Radio Corporation of America. As described in the said application, the positive rectangular pulse which is impressed upon the grid condenser 62 of the tube 61 is differentiated in an unsymmetrical manner, the pulse resulting from the front side of the rectangular pulse being of small amplitude because of the low grid-cathode impedance of the tube 61 which is maintained by the application of a positive voltage to the control grid, and the pulse resulting from the back side of the rectangular pulse being of comparatively large amplitude, since the differentiating circuit now includes the grid resistor 63. This last-mentioned pulse appears on the grid of the tube 61 with negative polarity whereby the more negative portion of the pulse is clipped off by the tube 61. Therefore, there appears in the plate circuit of the tube 61 a delayed pulse of positive polarity which is fed through a coupling condenser 70 to the control grid of the pentode 26. These delayed pulses key the pentode 26 to make it conducting only during the period of a black level in the composite signal, as will be seen by comparing Figs. 5 and 6.

The pentode 26 is in a nonconducting condition (that is, it is biased beyond "cut-off") between successive keying pulses as a result of a grid leak bias which is produced by the positive keying pulses driving the control grid 71 of the pentode slightly positive periodically to produce grid current flow. The cathode 72 of the pentode 26 is held substantially at ground potential for alternating currents by means of a by-pass condenser 76. However, the cathode 72 is held at a negative D.-C. potential with respect to ground and with respect to the pentode plate 73 by means of a suitable voltage source which, in the example illustrated, comprises a 60-cycle voltage supply 71, a rectifier 78, and a resistor 79 and smoothing condenser 81. This negative D.-C. potential is also the "level setting voltage" for the D.-C. reinsertion circuit.

The plate of the pentode 26 is connected through a conductor 86 and a resistor 87 to the control grid of the output tube 22 and to the grid side of coupling condenser 21 whereby condenser 21 may be either charged or discharged therethrough for the purpose of maintaining the proper bias on the output tube to clip off the exaggerated or stretched synchronizing pulses at the proper level with respect to black in the picture, as indicated in Fig. 8. The resistor 87 is not essential to the circuit operation and may be omitted in some cases.

The suppressor grid of the pentode 26 is preferably held slightly positive with respect to the cathode in order to reduce the pentode impedance during the time that it is conducting and functioning as a diode, as will be explained below. It is during this time that the coupling condenser 21 will get an additional charge if the amplitude

of the pedestal (black) has decreased with respect to the preceding pedestal.

The plate of the pentode 26 is also connected to ground through a high impedance resistor 88 whereby the coupling condenser 21 may discharge a certain amount therethrough when it is not receiving an additional charge through the pentode 26.

As indicated above, the voltage across the portion of resistor 79 between the tap 80 and ground is both the plate voltage for the pentode 26 and the "level setting" voltage. Actually, the tap 80 is adjusted for the proper "level setting" and it happens that in the circuit illustrated it is also a suitable voltage for the pentode plate 73. If a different voltage were required for the plate 73, the lower end of the resistor 88 could be connected to a positive voltage instead of to ground.

Since there is an A.-C. signal on the plate 73 impressed thereon through conductor 86, the D.-C. positive voltage on plate 73 must be greater than the amplitude of the A.-C. signal on the negative side of the A.-C. axis. Otherwise, the plate 73 would go negative and the pentode 26 could not be made conducting by the keying pulses. The resultant voltage on the plate 73 is very low, from one to five volts for example, whereby the pentode is operating on the steep part of its characteristic when it becomes conducting. Thus, referring to Fig. 7, the pentode 26 operates on the portion of the characteristic curve A below the dotted line x, the plate impedance of the pentode being very low in this region. The curve A of Fig. 7 is for the case where the suppressor grid of pentode 26 is positive with respect to the cathode, as previously described. It will be apparent that, in the region of low plate voltage, the curve A is much steeper (indicating lower plate impedance) than is the curve B, which represents the tube characteristic when the suppressor grid is at cathode potential.

Considering the D.-C. insertion action of pentode 26 more in detail, the resistor 88 is given a resistance value such that the coupling condenser 21 will discharge just enough between successive horizontal synchronizing pulses to permit the potential on the control grid of tube 22 to follow the low frequency variations for which it is desired to correct. It is evident that in this type of circuit the time constant for the discharge path of the condenser 21 is slow. On the other hand, the time constant of the charging circuit through the pentode 26 is fast.

To follow through a cycle of operation, first considering the circuit when there is no incoming signal, the coupling condenser 21 has been charged up to the plate voltage of amplifier tube 17 since there is a D.-C. path from the plate supply of tube 17 through the resistor 88 and conductor 86 to the grid side of the condenser 21.

Now assume a signal is received. Since the synchronizing pulses 13 and pedestals 14 (Fig. 5) are of negative polarity at the plate of tube 17, the condenser obviously will lose a certain amount of its original charge upon the occurrence of a synchronizing pulse. Also, the greater the amplitude of the pedestal 14 with respect to the A.-C. axis, the more of its charge the condenser 21 will lose.

The charge of condenser 21 will vary in accordance with the height of the pedestals 14 from the A.-C. axis (the keying of pentode 26 being only during pedestal), this being a circuit action that must take place if the grid of tube 22 is to

be set at a predetermined voltage level upon the occurrence of each synchronizing pulse.

If the pedestals 14 decrease in amplitude (become less negative), then, upon the occurrence of such a pedestal, the condenser 21 receives a slight additional charge through the pentode 26 acting similar to a diode during the time it is rendered conducting by the delayed keying pulse (Fig. 6). This charging circuit is through the conductor 86, the pentode 26, through the lower portion of resistor 79 (and also through by-pass condenser 76) to ground, and through ground to the plate circuit of tube 17. This additional charge always brings the grid of tube 22 substantially to the voltage of the tap 80.

If the pedestals 14 increase in amplitude (become more negative), the condenser 21 will continue to lose more of its charge through resistor 88 until the condenser 21 again receives a slight additional charge through the pentode 26.

It will be understood that, at the grid of tube 22, the D.-C. insertion must be in accordance with the height of the pedestal 14 rather than in accordance with the height of the synchronizing pulses 13 because, as shown in Fig. 5, the pulses 13 have been greatly increased in height at this point by the pulses added in from the conductor 18.

From Fig. 8, it is apparent that the undesired part of the synchronizing pulses 13 is clipped off by the output tube 22, the pedestal 14 being held at a fixed point with respect to the tube characteristic. Therefore, the tube 22 supplies to the transmitter 29 a composite signal having "black" in the picture at a fixed level as a result of the D.-C. insertion and low frequency correction and, also, having synchronizing pulses of the desired fixed amplitude.

The output tube 22 need not be of the cathode-follower type but, instead, may have the usual plate output. The type illustrated is conveniently employed when the tube is feeding into a cable as the impedances are easily matched.

For the purpose of illustrating a specific example, the values of various circuit elements are indicated in Fig. 1 in ohms, megohms, microfarads and micromicrofarads.

From the foregoing, it will be apparent that various modifications may be made in my invention without departing from the spirit and scope thereof.

I claim as my invention:

1. Picture transmission apparatus for the transmission of a composite signal comprising picture signals and periodically recurring synchronizing pulses, said apparatus comprising an input circuit for receiving said composite signal, means for applying direct current and low frequency correction to said received signal, means for adding to the synchronizing pulses of said corrected composite signal additional pulses to increase the amplitude of the synchronizing pulses in the resulting composite signal to a value greater than is desired in the final signal, and means for clipping off the tops of the synchronizing pulses in said resulting signal at a fixed level with respect to "black" in the picture.

2. Picture transmission apparatus for the transmission of a composite signal comprising picture signals and periodically recurring synchronizing pulses, said apparatus having an input circuit for receiving said composite signal, means for applying direct current and low frequency correction to said received signal, means for providing a signal comprising control pulses which

occur simultaneously with the synchronizing pulses in said corrected signal, means for adding said corrected composite signal and said last-mentioned pulses to increase the amplitude of the synchronizing pulses in the resulting composite signal to a value greater than is desired in the final signal, and means for clipping off the tops of the synchronizing pulses in said resulting signal at a fixed level with respect to "black" in the picture.

3. Picture transmission apparatus for the transmission of a composite signal comprising picture signals and periodically recurring synchronizing pulses, said apparatus having an input circuit for receiving said composite signal, means for applying direct current and low frequency correction to said received signal, means for producing pulses substantially free from picture signal which occur simultaneously with the synchronizing pulses in said corrected signal, means for adding said corrected composite signal and said last-mentioned pulses to increase the amplitude of the synchronizing pulses in the resulting composite signal to a value greater than is desired in the final signal, and means for clipping off the tops of the synchronizing pulses in said resulting signal at a fixed level with respect to "black" in the picture.

4. Picture transmission apparatus for the transmission of a composite signal comprising picture signals and periodically recurring control pulses which are set on pedestals of greater width than said pulses, said apparatus comprising an input circuit for receiving said composite signal, means for applying direct current and low frequency correction to said received signal, means for producing control pulses and for adding them to said corrected composite signal to increase the amplitude of the control pulses in the resulting composite signal to a value greater than is desired in the final signal, and means for clipping off the tops of the control pulses in said resulting signal at a fixed level with respect to "black" in the picture, said last means comprising a vacuum tube through which the said resulting signal is passed, a source of keying pulses each of which occurs later than the preceding control pulse and during the occurrence of a pedestal, and further comprising a direct current reinserting circuit for varying the bias of said vacuum tube in response to said keying pulses.

5. Picture transmission apparatus for the transmission of a composite signal comprising picture signals and periodically recurring control pulses which are set on pedestals of greater width than said pulses, said apparatus comprising an input circuit for receiving said composite signal, means for applying direct current and low frequency correction to said received signal, means for producing control pulses and for adding them to said corrected composite signal to increase the amplitude of the control pulses in the resulting composite signal to a value greater than is desired in the final signal, an electric discharge tube through which said resulting signal is passed, said tube having a voltage applied thereto which determines the level at which it clips off the tops of the control pulses in said resultant signal, and a direct current reinserting circuit which varies said voltage in accordance with the height of said pedestals as measured from the alternating current axis of said resultant signal.

6. Picture transmission apparatus for the transmission of a composite signal comprising

picture signals and periodically recurring control pulses which are set on pedestals of greater width than said pulses, said apparatus comprising an input circuit for receiving said composite signal, means for applying direct current and low frequency correction to said received signal, means for producing control pulses and for adding them to said corrected composite signal to increase the amplitude of the control pulses in the resulting composite signal to a value greater than is desired in the final signal, and means comprising an output tube for clipping off the tops of the control pulses in said resulting signal at a fixed level with respect to "black" in the picture, said last means comprising a direct current reinserting circuit including an electric discharge tube which is rendered conducting only after the occurrence of a control pulse and during the occurrence of a pedestal.

7. In apparatus for the transmission of a composite signal comprising picture signals and periodically recurring control pulses, a signal amplifier channel comprising an amplifier tube having a control electrode upon which said composite signal is impressed with the control pulses of positive polarity, means including a second amplifier tube for adding to the control pulses of said corrected composite signal additional control pulses to increase the amplitude of the control pulses in the resulting composite signal to a value greater than is desired in the final signal, said second amplifier tube having a control electrode, said two amplifier tubes having their input circuits connected in parallel relation with each other and in series with a coupling condenser, means for biasing the control electrode of the first amplifier tube sufficiently negative to prevent the control pulses applied thereto from causing grid current flow, and a resistor connected adjacent to the control electrode of the second amplifier tube and shunted by a condenser, said resistor and condenser having a time constant such that a bias voltage appears thereacross due to grid current flow in the second amplifier tube, means providing a discharge path for said coupling condenser only between picture signal intervals whereby the received signal is provided with direct current and low frequency correction, and means for clipping off the tops of the control pulses in said resulting signal at a fixed level with respect to "black" in the picture.

8. Apparatus for direct current and low frequency correction of a composite signal comprising picture signals and periodically recurring control pulses, said apparatus comprising an amplifier tube having a control electrode, a coupling condenser through which said signal is applied to said control electrode with the control pulses of positive polarity, a diode having its cathode connected to said control electrode and having its plate connected through a resistor to ground, means for impressing keying pulses through a second condenser upon said diode plate, the keying pulses occurring in substantially the same time relation as said control pulses, and a second diode having its plate coupled through said second condenser to the plate of the first diode and having its cathode connected through a resistor to ground, and a condenser connected in shunt to said resistor, the time constant of said last resistor and condenser being shorter than the time constant of the circuit including said first resistor and said second condenser.

9. In combination, an electric discharge tube

having a control electrode at which the direct current component of a signal is to be reinserted, a coupling condenser through which signal having recurring pulses of negative polarity is applied to said electrode, a pentode having its plate connected to said electrode and having its cathode connected to ground through a level setting voltage source, means for holding said pentode normally biased beyond cut-off for plate current, means for holding the suppressor grid of the pentode positive with respect to its cathode, a

grid leak resistor connected between said control electrode and ground, and means for making said pentode conducting periodically whereby said coupling condenser may receive a charge.

5 10. The invention according to claim 9 wherein in said last means comprises means for supplying positive polarity keying pulses to the control grid of the pentode, each of which occurs immediately after the occurrence of one of the first- 10 mentioned pulses.

KARL R. WENDT.
